UNITED STATES PATENT OFFICE.

BERTRAND A. PARKES, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA.

FABRIC-DRYING MACHINE.

1,125,707.

Specification of Letters Patent. Patented Jan. 19, 1915.

Application filed September 18, 1913. Serial No. 790,404.

To all whom it may concern:

Be it known that I, BERTRAND A. PARKES, of Philadelphia, in the county of Philadelphia, and State of Pennsylvania, have invented, certain new and useful Improvements in Fabric-Drying Machines, whereof the following is a specification, reference being had to the accompanying drawings.

This invention relates to fabric drying machines of that type in which the fabric to be dried is hung in looped form from an endless conveyer passing through the drying apparatus, as is shown and described in my co-pending application filed April 15th, 1913, Serial No. 761,244. In this type of apparatus it is desired to obtain the greatest capacity of looped fabric within the drying chamber as possible, and in the use of the apparatus of my co-pending application, it has been found that the web often partially falls over the next pole of the conveyer before the loop being formed is completed, thus shortening the length of the loop being formed and consequently correspondingly diminishing the capacity of the apparatus. Furthermore, at times, too much of the web is fed between a pair of poles, and consequently a longer loop is formed which drags on the bottom of the apparatus and becomes soiled.

One object of this invention is, therefore, to provide means for forming the loops in uniform lengths and thereby insure a full capacity.

Another object of the invention is to provide means for preventing the web falling over the next adjacent pole until the loop being formed is completed.

A further object of the invention is to provide means for positively feeding the web between adjacent poles, and consequently preventing any possibility of the web falling over the next succeeding pole before the loop is of the proper length.

These and other objects will in part be obvious, and will in part be hereinafter more fully described.

In the accompanying drawings, Figure I, is a side elevation showing a portion of a drying machine having my improvements applied thereto. Fig. II, is an end elevation thereof; and Figs. III, IV, V, VI and

VII, are enlarged detail elevations showing different forms of my invention.

By referring to the drawings generally, it will be seen that the fabric is fed under and over a pair of feed rolls, and thence successively between each adjacent pair of poles of the traveling conveyer. The poles clamp the web against a movable stop roll until the next loop is formed. Oftentimes, the web will fall upon the next succeeding pole before the loop being formed is completed, thereby shortening the loop and diminishing the capacity of the machine. In order to prevent such an occurrence, I have provided means which engage the web in advance of its engagement with either the conveyer or stop roll, and which include means for positively feeding the proper lengths of web successively between each pair of poles, thus preventing the web falling on to the next adjacent pole before the loop being formed is completed, and at the same time insuring a full capacity to the machine by forming the loops of uniform size.

The drying machine to which my invention is applied, consists generally of an enclosed casing 5, constituting the drying chamber, and moving in a vertical plane through this chamber is an endless conveyer 6, which includes the usual loop-supporting poles 7, said poles being spaced equal distances apart. The conveyer is moved at a uniform speed by any suitable driving means, not shown. The fabric 8, to be dried, is fed over an idle roll 9, supported on the frame above and in front of the conveyer, and is then fed under and over the feed rolls 10, and 11, respectively, said rolls being supported on the frame above the conveyer and between the idle roll 9, and the casing 5. The fabric then passes down to the conveyer and successively between each pair of poles. The web is clamped between the last pole and a movable stop roll 12, the latter being journaled in inclined slots 13, of supporting brackets 14. The clamping or stop rolls 12, serve to retain the loop last formed against being either shortened or lengthened while the next succeeding loop is being formed.

The above construction is disclosed in my co-pending application referred to above,

and, therefore, I have only described the same sufficiently to give a clear understanding of the present invention.

My invention consists broadly in placing a device in advance of the stop or clamping roll 12, which will prevent the web from falling upon the next adjacent pole while the loop being formed is completed. To this end, there are supported on the front 10 end of the casing 5, spaced brackets 15—15 which support upper and lower feed and guide rolls 16, and 17, respectively, which extend entirely across the machine. The web is fed in advance of the roll 16, and in 15 rear of the roll 17, and these rolls are driven in unison by intermeshing gears 18, and 19, respectively mounted on said rolls. The upper roll 16, is provided with a pulley 20, which is driven by a belt 21, from a pulley 20, mounted on the shaft 23, of the feed roll 10, the shaft 23, being timed with the conveyer to properly feed the web to the latter. The guide and feed rolls 16, and 17, are positioned relative to the clamping roll 12, to 25 feed the proper amount of web between each pair of poles 7, so that it is impossible for the web to drop upon the next adjacent pole until the loop being formed is completed. At the same time, by reason of the rolls 16, 30 and 17, being positively driven and timed with the conveyer, the proper lengths of fabric will be successively fed to each pair of poles 7, of the conveyer. It will be observed that the initial starting of a new loop 35 is not begun until the clamping roll has clamped the web of the loop last formed to the last or adjacent pole 7. The clamping roll thus prevents the last loop, which has been previously formed of proper size, from 40 being varied by the formation of a new loop.

In Figs. I and II, I have shown two rolls 16, and 17, for accomplishing the object of my invention, but I do not wish to be limited to this construction, as other means such 45 as are shown in Figs. III to VII, inclusive may be employed if desired, and without departing from the spirit of my invention.

In the construction shown in Fig. III, the upper roll is dispensed with, and a guide board 24, is substituted therefor, said board being suitably supported by the casing 5. This board guides the web between each 50 pair of poles 7, and the roll 17, positively feeds said web.

55 In Fig. IV, the bracket 14, supports a pivoted and weighted clamping member 25, whose function is identical with that of the clamping roll 12. In this figure I have provided the guide board 24, shown in Fig. IV, 60 but have substituted for the feed roll 17, of said figure, an endless conveyer 26, for the web which positively feeds said web between each pair of poles 7, of the main conveyer.

Fig. V, shows the stop or clamping roll 65 12, and combined feed and guide rolls 30, and 31, arranged one above the other and engaging one side only of the web.

In the structure shown in Fig. VI, the feed rolls 10, and 11, are intermittently actuated by any suitable means not shown, and the auxiliary feed roll 17, is correspondingly actuated through the belt drive. Associated with this form is the guide board 24, and the web is fed between this 70 board and the roll 17. Each pole 7, is provided with teeth 35, for engaging the web. In operation, when the space between a given pair of poles is in proper position, the feed rolls 10, 11, and 17, are actuated, thus 75 feeding the proper amount of the web between said poles. The teeth 35, in effect, perform the same function as the clamping roll 12, previously described, the teeth pressing into the web as the latter passes under 80 the guide board and thereby retain the completed loop against becoming shortened or lengthened.

The structure embodied in Fig. VII, is similar to that shown in Fig. VI, except the 90 feed roll 17, and guide board are removed, and opposed endless conveyers 36, 36, are substituted and are disposed on the opposite sides of the web.

From the foregoing it will be seen that I 95 have provided means for successively forming loops of uniform size and that means are provided for preventing the initial starting of the next adjacent loop until the loop being formed is completed, thus causing the 100 machine to always operate in full capacity.

While I have described my invention as especially adapted for use in connection with an apparatus for drying fabrics, it will be understood that my improved feeding 105 mechanism for placing and forming successive loops of uniform size may be also used in connection with machines for shrinking cloth, dampening cloth or other classes of machines wherein the fabric may be placed 110 in loops. I, therefore, do not limit myself to a feeding device for a drying machine, but the scope of the invention is set forth in the appended claims.

It is obvious that minor changes in the 115 details of construction and the arrangement of parts may be made without departing from the spirit of the invention, as set forth in the appended claims.

Having thus described my invention, I 120 claim:

1. A drying apparatus comprising a continuously traveling endless conveyer, spaced supporting poles fixed to said conveyer from which loops of fabric are to be suspended, a device for clamping the web against a pole for starting a new loop of fabric, and means for positively feeding 125

loops of fabric between the poles at a point adjacent said clamping device.

2. A drying apparatus comprising a continuously traveling endless conveyer, spaced 5 supporting poles fixed to said conveyer from which loops of fabric are to be suspended, a device for clamping the web against a pole for starting a new loop, positively actuated feeding rolls for feeding the web between

the poles at a point close to said clamping device.

In testimony whereof, I have hereunto signed my name at Philadelphia, Pennsylvania, this 16th day of September, 1913.

BERTRAND A. PARKES.
